(57) **CLAIM**

The ornamental design of a flashlight, as shown and described.

DESCRIPTION

FIG. 1 is a front perspective view of our new design for a flashlight.

FIG. 2 is a front elevation view of the flashlight shown in FIG. 1.

FIG. 3 is a back side elevation view of the flashlight shown in FIG. 1

FIG. 4 is a top plan view of the flashlight shown in FIG. 1.

FIG. 5 is a bottom plan view of the flashlight shown in FIG. 1.

FIG. 6 is a right elevation view of the flashlight shown in FIG. 1, the left side being a mirror image

FIG. 7 is a front perspective view of an alternate embodiment our new design for a flashlight, that differs from the first embodiment only in that has an additional strap attachment point, it being understood that bottom surface is same as the first embodiment.

FIG. 8 is a front elevation view of the flashlight shown in FIG. 7.

FIG. 9 is a back side elevation view of the flashlight shown in FIG. 7

FIG. 10 is a top plan view of the flashlight shown in FIG. 7; and,

FIG. 11 is right elevation view of the flashlight shown in FIG. 7, the left side being a mirror image.

The broken line showing is for illustrative purposes only and forms no part of the claimed design.
